Emery Varney, Blair & Hogan.

UNITED STATES PATENT OFFICE.

ANSON J. BENTLEY, OF NILES, OHIO.

FREEZING CAN.

Application filed August 24, 1920. Serial No. 405,693.

To all whom it may concern:

Be it known that I, ANSON J. BENTLEY, a citizen of the United States, and a resident of the city of Niles, in the county of Trumbull and State of Ohio, have invented an Improvement in Freezing Cans, of which the following is a specification.

This invention aims to improve ice-freezing cans wherein air or fluid is conducted to the interior of the cans near the base thereof, and more particularly the invention relates to the air or fluid-conducting apparatus and to the method of attaching the same to the cans.

15 A selected embodiment of the invention is illustrated in the drawings, wherein—

Figure 1 is a perspective view of an ice-freezing can;

Figure 2 is a detail view of the fluid-conducting apparatus in normal position;

Figure 3 is a sectional view of the apparatus taken on the line 3—3 of Fig. 2;

Figure 4 is a perspective view of a fixture;

Figure 5 is a sectional view of the fixture 25 taken on the line 5—5 of Fig. 4;

Figure 6 is a view of the mandrel; and

Figure 7 is a view in section of a modified form of tube in position in the groove of the can.

30 In the particular embodiment of my invention selected for illustration herein, and shown in the drawings, referring first to Fig. 1, a freezing can 1 of desired shape and character such, for instance, as generally employed in the manufacture of artificial ice is 35 illustrated, the same having the base 2 and the sides 3, 4, 5 and 6. Preferably the sides 3 and 5 are wider than sides 4 and 6 so that the ice cake formed therein will be of the 40 well known rectangular shape.

In the manufacture of the artificial ice cakes these freezing cans are usually filled with water and placed in a brine solution, and it is customary to agitate the water during the freezing. To this end the agitation or stirring of the water is preferably accomplished by introducing air or fluid into the water near the bottom of the can. The air may be conducted to the lower end of the can by any well known means, as for example a usual tube 7 assembled in a channel 8 which is impressed in one of the sides of the freezing can. Tubes having desired shapes of cross sections may be employed and the channels will be suitably formed, as shown, to receive the same. The air is preferably in-

roduced into the interior of the can at a point just above the base and for this the side of the can, preferably as in the channel portion, is provided with an aperture 9. 60 The tube 7 as assembled in the channel preferably has its lower end located adjacent this opening 9, and a fixture 10, as illustrated in Figs. 4 and 5, is assembled in the lower end of the channel and over the end of the tube to direct the air from the end of the tube to and through the aperture or opening 9. The fixture is conveniently made as a fitting or clip stamped from sheet metal. After these fluid-conducting members have 65 been assembled in the freezing can they are soldered or otherwise suitably held in position. The fixture 10 (see Fig. 4) has a convex part 11 for fitting the channel below the opening 9 and has a concave or grooved part 70 12 for receiving the end of the tube. A shoulder 13 is formed in the fixture between the convex and concave portions and functions to guide the air from the end of the tube to the interior of the can. This fixture 75 or clip is desirable as it is quickly and cheaply manufactured and may be quickly assembled and held in position.

A convenient method of assembling the fluid-conducting apparatus in proper position consists in assembling the mandrel 14, illustrated in Fig. 6, in the tube 7 by inserting the end 15 of the mandrel in the tube. The tube and mandrel are then placed in the channel 8, as illustrated in Fig. 3, with the 80 free end of the mandrel extending to the interior of the can and preferably contacting with the metal of the can at the top of the opening 9. The fitting 10 is then placed in the channel and over the end of the tube. 85 The lowest end of the convex part of the fitting contacts with a shoulder 16 formed in the end of the channel where it graduates to the original outline of the can. The shoulder 13 in the fixture is properly positioned 90 opposite the opening 9 when the end of the fixture sets on the shoulder 16. A pocket is formed between the channel and the concave part 12 of the fixture for receiving the end 95 of the tube, and flanges 17 and 18 conform to the shape of the channel to assist in holding the fixture in position. Next the solder or other fastening means is applied to hold the tube and fixture to the freezing can and to each other. The mandrel during this step 100 operates to prevent the solder from filling the opening in the tube or the opening 9. 105

After the soldering is completed the mandrel is removed, and an unobstructed passageway for air or fluid from the top of the freezing can to the interior thereof near its base is obtained.

Referring to Fig. 7, the fixture is shown as applicable to the lower end of a tube which is bent to partially enter the opening 9. In this arrangement the holding means such as solder is applied to the fixture and to the channel and to parts of the tube extending above the fixture thus firmly holding the tube in position. In assembling the tube with the bent end the use of the mandrel 14 is obviated as the tube is laid in the channel 8 with part of its lower end held in the opening 9 thereby positioning itself and filling the opening 9 so that the solder will not enter and fill the air passage.

The invention may be variously embodied and the particular form of apparatus herein shown may be modified within the scope of the subjoined claims.

I claim:

- 25 1. A freezing can for use in the manufacture of ice having one wall inwardly grooved from the top of the can substantially to the bottom thereof, the inner wall of said groove being perforated near its lower end, an air tube located and fastened securely in said groove and extending from the upper edge of the can to a point adjacent the perforation in the groove, and a fixture forming a fluid tight connection between the tube and the interior of the can fitting said groove and provided with a longitudinal recess in its inner side which cooperates with the groove bottom to receive the end of the tube adjacent the perforation.
- 30 2. A freezing can for use in the manufacture of ice having a U shaped channel formed in one of its sides and extending substantially the full length thereof and having an opening in said channel leading

to the interior of said can, an unbent air tube located in said channel, and a grooved fixture having a shoulder therein and being mounted in said channel with said shoulder opposite said opening, said fixture receiving the end of said tube and effecting a connection between the end of the tube and the opening in the groove.

3. A freezing can for use in the manufacture of ice having a U-shaped channel formed in one of its sides and extending substantially the full length thereof and having an opening in said channel leading to the interior of said can, an air tube extending along said channel from the top of the can substantially to said opening and a stamped fixture forming an air tight connection between the air tube and the opening, said fixture being generally of U-shape in cross section, fitting in said channel and having a portion of the fixture reversely grooved forming with the channel bottom a recess to receive and fit the air tube.

4. A freezing can for use in the manufacture of ice having a U-shaped channel formed in one of its sides and extending substantially the full length thereof and having an opening in said channel leading to the interior of said can, an air tube extending along said channel from the top of the can substantially to the opening and a stamped fixture substantially of U-shape in cross section fitting in said channel at the opening, having a portion above the opening reversely grooved to form with the channel bottom a cylindrical recess to receive the air tube, said fixture forming an air tight connection between said air tube and the interior of the can.

In testimony whereof, I have signed my name to this specification this 21st day of August, 1920.

ANSON J. BENTLEY.
